Attorney

UNITED STATES PATENT OFFICE.

JASON LEE LAWTON, OF BUFFALO, NEW YORK.

EGG-BEATER.

1,268,586.

Specification of Letters Patent. Patented June 4, 1918.

Application filed April 13, 1918. Serial No. 228,414.

To all whom it may concern:

Be it known that I, JASON LEE LAWTON, a citizen of the United States, residing at Buffalo, in the county of Erie and State of 5 New York, have invented certain new and useful Improvements in Egg-Beaters, of which the following is a specification, reference being had to the accompanying drawings.

10 This invention relates to an improved egg beater, and has for its primary object to provide a device for this purpose which can be easily manipulated with a minimum of manual labor to thoroughly beat eggs, or 15 other fluid or semi-fluid materials.

It is another important object of the invention to provide an egg beater which is strong and durable in its construction, and wherein the several operating parts for the 20 beater elements are housed and protected so that their accidental injury or interference with their proper operation is obviated.

It is one of the detail objects of the invention to provide an egg beater embodying 25 a rotatable head and a cylinder or housing fixed to said head, beater elements secured to the head and the housing, a member longitudinally movable within the housing and operatively connected to said head, and a 30 spring within the housing resisting the movement of said member in one direction.

It is also a further general object of the invention to improve and simplify the construction of devices of the above character 35 so that the same may be produced at small manufacturing cost and to render the same efficient and serviceable in practical use.

With the above and other objects in view, the invention consists in the improved combination, construction and relative arrangement of the several parts as will be herein-after more fully described, subsequently claimed and illustrated in the accompanying drawing in which similar reference 45 characters designate corresponding parts throughout the several views, and wherein:

Figure 1 is a longitudinal sectional view of an egg beater constructed in accordance with the preferred embodiment of my invention;

Fig. 2 is a section taken on the line 2—2 of Fig. 1;

Fig. 3 is an enlarged detail section taken on the line 3—3 of Fig. 1; and

Fig. 4 is a horizontal section taken on the 55 line 4—4 of Fig. 1.

Referring in detail to the drawing, 5 designates a head plate which may be of circular or other form in plan, said plate being provided with a central opening there- 60 in having a spiral thread or rib 6.

To the outer edge of the head plate 5 at diametrically opposite points, the terminals of the metal straps 7 are suitably secured. The end portions of these straps extend in 65 parallel relation for a suitable distance, while the medial portions thereof are formed into the opposed laterally bowed sections 8. The medial portions of the respective metal straps connecting the bowed 70 sections 8 thereof are disposed in intersecting relation to each other.

One end of an elongated cylindrical metal housing or cylinder 9 is fixed to the head plate 5, and to the other or closed end of this 75 cylinder, the terminals of the additional metal straps 10 are securely fixed. These latter straps are also provided with the oppositely bowed portions 11 disposed inwardly of and in spaced relation to the 80 bowed portions 8 of the straps 7. The medial portions of the straps 11 are also disposed in intersecting relation to each other and upon the intersecting portions of the straps 7. These intersecting portions of 85 the several beater straps may be riveted or otherwise permanently secured together. Preferably, the bowed portions 8 and 11 of the beater straps, which are disposed in the same transverse plane, are connected to each 90 other by the bracing plates or webs shown at 12 and which also serve as additional agitating means for the eggs or other materials.

An operating rod 13 is engaged through the opening in the head plate 5 and is provided with a spiral groove 14 in its periphery to receive the spiral thread or rib 6 on the head plate. To the end of this rod, extending within the cylinder or housing 9, a plate or disk 15 is fixed. A handle 16 of 100

any suitable form is loosely engaged upon the bolt 17 fixed in the other end of the rod 13 and projecting longitudinally therefrom.

A coil spring 18 is arranged within the 5 cylindrical housing 9 and bears at one of its ends against the closed end wall of said housing. To the other end of this spring a metal disk 19 is fixed, and this disk is formed with a central conical stud 20 en- 10 gaged in a bearing recess or cavity formed in the opposed face of the plate 15. Thus frictional contact between the plates 15 and 19 is prevented.

In the operation of the device above de- 15 scribed, and assuming that the spring 18 is expanded and the rod 13 is in its normal position, the bowed portions of the metal beater straps, are disposed within the eggs or other material contained in a suitable receptacle; and the rod 13 is then forced longitudinally through the head plate 5 against the action of the spring 18. In this movement of the rod, the rib or thread 16 engaged in the spiral groove 14 causes the head plate 20 5, the cylinder 9 and the beater straps connected to said head plate and cylinder to rotate with respect to the rod 13. Of course in the rotation of the cylinder or housing 9, the spring 18 also rotates therewith, as 25 said spring is gradually compressed. The plate 19 on the end of the spring 18, being spaced from the plate 15, may also freely rotate with respect to the latter plate. When the handle 16 is released, the spring 18 ex- 30 pands and reverses the axial movement of the rod whereby the rotation or turning movement of the beater members and the parts connected thereto is also reversed. Thus, the thorough agitation of the eggs or 35 other materials with relatively little manual exertion, is obtained.

From the foregoing description taken in connection with the accompanying drawing, the construction, manner of operation and 40 several advantages of the invention will be clearly and fully understood. The device as a whole, is relatively simple and strong and durable in its construction. By providing the housing 9 for the operating rod and 45 the spring 18, these parts are protected, so that the material being agitated cannot collect thereon or other foreign matter find its way between the coils of the spring or the plates 15 and 19 and interfere with the 50 proper operation of the device. I have illustrated in the accompanying drawing, a certain number and arrangement of the metal beater straps, but it is manifest that a greater or less number of such straps may 55 be employed and they may be otherwise constructed than as herein shown. The device is also susceptible of many other modifications in the form, proportion and ar-

angement of its several elements, and I therefore reserve the privilege of adopting 65 all such legitimate changes as may be fairly embodied within the spirit and scope of the invention as claimed.

I claim:—

1. A beater of the character described in- 70 cluding a head plate, a housing fixed at one end to the head plate, beater members fixed to said housing and the head plate, and means for rotating the housing and the head plate, said means being operatively ar- 75 ranged within the housing.

2. A beater of the character described in- 80 cluding a head plate, a housing fixed at one end to the head plate, beater members fixed to said housing and the head plate, and means for alternately rotating the housing and the head plate and the beater members connected thereto as a unit in opposite directions, said means being operatively ar- 85 ranged within the housing.

3. A beater of the character described in- 90 cluding a head plate, a housing fixed at one end to the head plate, beater members fixed to said housing and the head plate, means for alternately rotating the housing and the head plate and the beater members connected thereto as a unit in opposite directions, said means including a member axially movable within the housing and operatively engaged with the head plate to rotate the latter, and a spring arranged within the housing and resisting the movement of said member in one direction.

4. A beater of the character described in- 100 cluding a head plate, a housing fixed at one end to the head plate, beater members fixed to said housing and the head plate, a rod axially movable within the housing and operatively engaged with the head plate to rotate said plate in reverse directions in the re- 105 verse axial movements of said rod, and means arranged within the housing and rotatable therewith to resist the axial movement of said operating rod in one direction.

5. A beater of the character described in- 110 cluding a head plate, a housing fixed at one end to the head plate, beater members fixed to said housing and the head plate, a rod axially movable within the housing and operatively engaged with the head plate to 115 rotate said plate in reverse directions in the reverse axial movements of said rod, a coil spring arranged within said housing and rotatable therewith, said spring resisting the axial movement of the rod in one direction, 120 and means on one end of the spring rotatably engaged with the end of said rod.

6. A beater of the character described in- 125 cluding a head plate, a housing fixed at one end to the head plate, beater members fixed to said housing and the head plate, a rod

axially movable within the housing and operatively engaged with the head plate to rotate said plate in reverse directions in the reverse axial movements of said rod, a coil spring arranged within said housing and rotatable therewith, said spring resisting the axial movement of the rod in one direction, a plate fixed upon the end of the rod, and a plate fixed on the opposed end of said spring

and having a bearing stud rotatably engaged 10 with said first named plate.

In testimony whereof I hereunto affix my signature in the presence of two witnesses.

JASON LEE LAWTON.
